GRINDING MACHINERY

Frederick S. Haas, Cincinnati, Ohio, assignor to
Cincinnati Grinders Incorporated, Cincinnati,
Ohio, a corporation of Ohio

Application March 7, 1930. Serial No. 434,077

8 Claims. (Cl. 51—238)

This invention relates to improvements in machine tool structures and especially to improvements in cylindrical grinders.

One of the principal objects of the invention is to provide improved means for backing up or supporting a work piece during grinding.

Another object of the invention is to provide a universal back rest or steady rest adapted to be utilized for different sizes of work pieces through a relatively wide range.

Another object of the invention is the provision of an improved back or steady rest for use with grinding machines that may also serve as a sizing device to apprise the operator when the

work piece has been reduced to the desired size.

Other objects and advantages of the present invention should be readily apparent by reference to the following specification considered in conjunction with the accompanying drawing forming a part thereof and it is to be understood that any modifications may be made within the exact structural details without departing from or exceeding the spirit of the invention.

Figure 1 is a fragmentary elevational view of a grinding machine embodying the improvements of this invention.

Figure 2 is a sectional view taken on line 2—2 of Figure 1.

Figure 3 is a fragmentary sectional view taken on line 3—3 of Figure 1.

Figure 4 is a fragmentary sectional view taken on line 4—4 of Figure 2.

Throughout the several views of the drawing similar reference characters are employed to denote the same or similar parts.

In the drawing the numerals 5 indicates the bed or support having mounted thereon for longitudinal translation relative thereto the work supporting table. On opposite ends of the table 6 is adjustably mounted, the head stock 7 and tail-stock 8 respectively supporting centers 9 and 10 adapted to terminally engage the work piece 11 to determine the axis about which the work piece rotates and for presenting same to the grinding wheel 12.

The work piece may be of considerable length and during the grinding operation is apt to be bent or sprung thereby preventing formation of a true cylindrical work piece. Heretofore, steady rests or back rests have been utilized but were limited in their capacity and necessitated the use of a plurality of rests, one for each size of work within relatively small limits. It is contemplated by this application to provide a steady or back rest that may be used with equal facility with

work pieces of different sizes throughout a relatively large range. Accordingly, a frame or support member 13 is provided having finished angularly related faces 14, 15 and 16 formed thereon to engage correspondingly finished and angularly related faces on the work supporting table 16.

The frame or support 13 is provided with upstanding lugs 17 through which clamping bolts 18 extend having on their lower ends a clamp shoe 19 substantially L shaped in cross section having one leg 20 thereof engaged beneath a ledge or shoulder 21 formed on the work support of table 16.

The frame or support 13 is provided with bores 22 and 23 having their axes extending at an acute angle to one another respectively supporting and guiding a rod 24 and a slide block 25. The rod 24 abuts on one end with an adjusting screw 26 threaded into the counter-bore 27 formed in bore 22. An actuating handle or knob 28 is pinned or otherwise secured to the screw 26 and a pair of lock nuts 29 are threadedly received by the screw 26. The other end of the rod 24 abuts a lug or ear 30 integral with pinion 31 and rotatable about pivot shaft 32. The teeth of the pinion 31 engage rack teeth 33 formed on slideable member 34. Intermediate its ends the rod 24 is guided by a support 35 journaled in suitable bearings 36 and 37 formed in side walls 38 and 39 of housing 13.

From the foregoing it will be noted that if knob 28 were rotated to feed the screw 26 into the bore 27, rod 24 would be axially actuated to rotate pinion 31 in a counter-clockwise direction slidably actuating member 34 upwardly through its guide sleeve 40 toward the axial center of the work. The sliding member 34 has secured to it by means of a cap screw 41 a shoe or the like 42 having engagement at 43 with the outer surface 95 of the work piece. This shoe is so positioned as to take up the cut thrust of the grinding wheel or other tool 12 since it rotates downwardly as respects the surface of the work piece or in a counter clockwise direction as indicated by the arrow in Figure 2.

The slide block 25 is actuated through the bore 23 by means of a screw or the like 44 having a swivel connection as at 45 therewith. The screw 44 is threadedly received in a threaded bore 46 formed in nut 47 in turn threadedly secured in the end of bore 23. An actuating knob 48 is pinned or otherwise secured to the outer end of the screw 44 and a pair of lock nuts 49 are threaded on to the screw 44. By actuating the screw 44 through

the knob 48 the slide block 25 is reciprocated through the bore 23 toward and from the axial center of the work piece 11.

Secured to the slide block 25 by means of a cap screw or the like 50 is a shoe 51 for contact as at 52 with the surface of the work piece. This shoe is so positioned as to take up the thrust on the work piece due to the feeding of the grinding wheel or the like toward the center of the work. The sliding block 25 and sliding member 34 are guided in their reciprocating motion by means of set screws 53 and 54 having titts 55 and 56 extending into the slots 57 and 58, formed respectively in the slide block 25 and sliding member 34. Each of the shoes 42 and 51 are utilized through a given range depending on the amount of reciprocation of the slide block 25 and sliding member 34.

As noted above the axes of the shoes 42 and 51 and the sliding members 34 and 25 extend at an obtuse angle to one another and they intersect at a point co-incident with the center of the work piece being supported thereby. This point of intersection is in the same plane as the axis of rotation of the grinding wheel. By this construction more than ninety degrees of the work piece is included between the points of contacts of the shoes therewith and the shoes act as clamping members supplementing one another to prevent jumping of the work piece in addition to taking up the thrusts as above noted. This relationship between the work piece and shoes is at all times maintained regardless of the size of work piece being supported thereby.

To adapt the steady rest for a different size of work piece, different size shoes may be substituted for shoes 42 and 51; for instance, to support a work piece of the size corresponding to the broken lines 59 a shoe extending to the broken line 60 would be substituted for shoe 51 while a similar shoe extending to the broken line 61 would be substituted for the shoe 42. Likewise, if it were desired to utilize the steady rest for smaller work as indicated by broken line 63 a shoe of a length extending from the slide block 25 and 34 to the surface of the work piece 63 would be substituted for the shoes 51 and 42. All of these shoes are exact duplicates of one another except for length and each is provided with a bore 64 through which the head of screws 41 and 50 pass to engage a shoulder 65 formed by flange 66 at the lower end thereof. Flange 66 is surrounded by a reduced portion 67 received in a counter-bore 68 formed in the adjacent end of slide block 25 and sliding member 34. A pin 69 is carried by the slide block 25 and sliding member 34 and cooperates with a bore or the like 70 formed in the shoe adjacent the reduced portion 67 thereon for positioning the said shoes relative to their actuating members.

It will be understood that any number of similar shoes may be provided and thereby change the capacity of the back or steady rest from the maximum to the minimum.

In practice, and when working a number of similar articles, such as pinion shafts, studs, piston pins or the like which are to have the same operation performed on each of them, the slide block 25 and sliding member 42 are adjusted during the finishing of the first article to the exact sizing whereupon the lock nuts 29 and 49 are brought up against the face of housing 13 and nut 47 respectively and locked in position. The screws 26 and 44 are then backed away to retract the shoes 42 and 51 and the finished work piece

replaced by an unfinished one and the machine cycle reinitiated. As the grinding or other operation on the present work piece continues the shoes 42 and 51 are adjusted and the faces thereof kept in engagement with the surface of the work piece. As soon as the lock nuts 29 and 49 abut the face of housing 13 and nut 47 the work piece has been reduced to the desired size and the infeed of the grinding wheel or other tool is stopped. The finished work piece is then replaced by another unfinished one and the cycle repeated until the last of the lot is complete.

From this it should be noted that the lock nuts act as a sizing device to apprise the operator when the work piece has been reduced to substantially the desired size. It should also be noted that the lock nuts need not be further adjusted except when changing or resetting the machine for operation on a different size or kind of work piece.

As was noted above the shoes 42 and 51 may be used for different size of work through a certain definite range for instance for work pieces from 10 inches to 11 inches in diameter and a different pair of shoes substituted therefor for work ranging through another band. By this construction the proper shoes may be provided for each band from the maximum of the machine with which the back or steady rest is employed, such as a 14 or 16 inch cylindrical grinder, down to the desired minimum, such as 6 or 4 inches in diameter or even smaller if desired. Therefore, as many as 12 or more pairs of shoes may be provided for use with the same compact rigid frame member and associated mechanisms for supporting and controlling work pieces ranging from four inches, for example, up to 16 inches, for example, in diameter. The shoes may be readily substituted one for the other since it is only necessary to remove the center capscrew such as 41 and 50 and the one shoe lifted from the seat formed in the slide-block or sliding member and the other shoe thereon and the capscrew reinserted through the bore therein and secured home.

What is claimed is:

1. In a device of the class described, the combination of a frame, a steady rest shoe carried thereby and positioned beneath a work piece to take up the cut thrust of a rotating tool, a second steady rest shoe carried by the frame positioned in opposition to the tool to take up the lateral thrust thereof, means for actuating one of the shoes axially of itself including a sliding member having rack teeth formed thereon, a pivotally mounted pinion having the teeth thereof engaging the rack teeth, a lug extending from the pinion, a slide bar engaging the lug and a screw for actuating the slide bar to rotate the pinion and adjust the sliding member, means for adjusting the remaining shoe axially of itself and means for guiding the members during their movement.

2. In a machine tool organization, the combination with a reciprocating table having a ledge formed thereon, a rotating tool adapted to be moved toward the table, a frame member having a pair of apertured upstanding lugs, a clamp bolt extending through each aperture, an L shaped clamp head on each bolt having one leg thereof in engagement with the ledge on the table to clamp the frame thereto, a pair of axially shiftable steady rest shoes carried by the frame having their axes disposed at an angle of more than ninety degrees and intersecting one another at a point along the axis of the work and positioned

- one beneath the work piece to take up the cut thrust of the rotating tool and the other positioned opposite the tool to take up the lateral thrust thereof and means for axially shifting the shoes toward the axis of the work to maintain contact thereof with the surface of the work. 8

3. In a steady rest mechanism the combination of a frame, a sliding member mounted in the frame, a steady rest shoe secured to the member, the said member having rack teeth thereon, a mutilated pinion for engagement with the rack, and means for actuating the pinion to axially adjust the sliding member and shoe. 10

4. In a steady rest mechanism the combination of a frame, a sliding member mounted in the frame, a steady rest shoe secured to the member, the said member having rack teeth thereon, a mutilated pinion for engagement with the rack, means for actuating the pinion to axially adjust the sliding member and shoe, said means comprising a lug extending from the pinion, a bar guided in the frame and contacting the lug, and means for actuating the bar. 15

5. In a steady rest mechanism of the class described the combination of a frame, a pair of sliding members mounted in the frame for axial adjustment relative thereto through a definite stroke from a fully retracted position to a fully advanced position, a first pair of steady rest shoes removably securable to the members for movement therewith from the fully retractable position to the fully advanced position and determining the band of diameters of work adapted to be supported thereby, individual adjusting means for each of the members and having a range of adjustment equal to the scope of movement of the members, and a second pair of steady rest shoes removably securable to the sliding members whereby adjustment of the members through the range of the adjusting means determines a second band of work diameters to be supported thereby, which second band of diameters commences where the first band of diameters stops, each of the sliding members having formed therein a seat, and each of the shoes having formed thereon a seat complementary to the sliding member seats. 20

6. In a steady rest mechanism the combination of a frame, a pair of sliding members mounted in the frame for axial adjustment relative thereto through a definite stroke from a fully retracted position to a fully advanced position, a first pair of steady rest shoes removably securable to the members for movement therewith from the fully retractable position to the fully advanced position and determining the band of diameters of work adapted to be supported thereby, individual adjusting means for each of the members and having a range of adjustment equal to the scope of movement of the members, and a second pair of steady rest shoes removably securable to the sliding members whereby adjustment of the members through the range of the adjusting means determines a second band of work diameters to be supported thereby, which second band of diameters commences where the first band of diameters stops. 25

7. In a steady rest mechanism of the class described the combination of a frame, a pair of sliding members mounted in the frame for axial adjustment relative thereto through a definite stroke from a fully retracted position to a fully advanced position, a first pair of steady rest shoes removably securable to the members for movement therewith from the fully retractable position to the fully advanced position and determining the band of diameters of work adapted to be supported thereby, individual adjusting means for each of the members and having a range of adjustment equal to the scope of movement of the members and a second pair of steady rest shoes removably securable to the sliding members whereby adjustment of the members through the range of the adjusting means determines a second band of work diameters to be supported thereby, which second band of diameters commences where the first band of diameters stops, each of the sliding members having formed therein a seat, and each of the shoes having formed thereon a seat complementary to the sliding member seats. 30

8. In a steady rest mechanism of the class described the combination of a frame, a pair of sliding members mounted in the frame for axial adjustment relative thereto through a definite stroke from a fully retracted position to a fully advanced position, a first pair of steady rest shoes removably securable to the members for movement therewith from the fully retractable position to the fully advanced position and determining the band of diameters of work adapted to be supported thereby, individual adjusting means for each of the members and having a range of adjustment equal to the scope of movement of the members, and a plurality of pairs of steady rest shoes individually, removably securable to the sliding members whereby adjustment of the members through the range of the adjusting means determines additional bands of work diameters to be supported thereby, each of which additional bands of work diameter commences where the other stops. 35
